GRENADE LAUNCHING TUBE AND AUXILIARY CARTRIDGE THEREFOR

Filed April 19, 1944

UNITED STATES PATENT OFFICE

2,432,539

GRENADE LAUNCHING TUBE AND AUXILIARY CARTRIDGE THEREFOR

Charles Robert Olsen, Philadelphia, Pa.

Application April 19, 1944, Serial No. 531,840

2 Claims. (Cl. 42-1)

(Granted under the act of March 3, 1883, as amended April 30, 1928; 370 O. G. 757)

1

The invention described herein may be manufactured and used by or for the Government for governmental purposes without the payment to me of any royalty thereon.

The invention relates to means for launching grenades and other projectiles from rifles, carbines, projectors, and the like, and has for an object to provide means for increasing the practicable range of these projectiles without risk of injury to the rifles or their mechanism, and without increased risk to personnel beyond that to be expected in use of projecting devices generally for such purposes.

It is a special purpose of the invention to provide an auxiliary propellant charge which will become effective immediately succeeding and continuing the initial pressure peak in the barrel resulting from the firing of the conventional grenade launching ammunition round or the like. The latter has been designed to produce a peak of pressure in the barrel of the rifle and the launcher attached, well below the safety limit of the rifle and tail tube of the grenade, and as an excess of such pressure at any time involves risk of bursting or other injury to the weapon, or tail tube and personnel, it has not been found practicable to merely increase the charge of propellant in the gun so as to obtain greater range, for the reason that the resultant effect would be a pressure peak far beyond a safe limit for the proper use of the rifle. It has therefore been a guiding motive in the invention to preserve the benefit of the use of a reasonably fast burning powder in the grenade launcher cartridge, so that a peak pressure will be developed promptly during the initial movement of the grenade and to implement this by an immediately following ignition of an explosive which will add to the gases already acting against the grenade, in sufficient quantity to continue or produce a renewed and relatively flat pressure peak well before the grenade leaves the launcher.

A further aim is to present a novel means for obtaining the augmentation of propulsion in such devices.

An important desideratum in the invention is the formation of a novel auxiliary cartridge for producing the effects and functions desired.

A very important object in view is to enable the use of standard matériel (including rifles and carbines, launchers, and grenades) already in hand and use, for launching grenades, signals, rockets and other projectiles, without change, except to the extent of the simple addition of an auxiliary cartridge which may be a unitary element of the grenade, or may be manually placed in loading.

A further important object of the invention is to provide an improvement as indicated above 60

2

which may be used to fire any of the conventional grenades, or ground signals, chemical containers, or rocket-propelled devices meant to be fired from a projector, rifle, or carbine.

5 Where a prior carbine, grenade-launching cartridge, launcher, and grenade are employed, a velocity of 145 feet per second just beyond the muzzle has been the optimum, but my invention has produced velocities of 220 feet per second without exceeding the safe pressure limits of the arm. The range attained with the mentioned prior matériel, approximates 202 yards, more or less, when the carbine is given an elevation of 45 degrees; while with my invention a range of 390 yards has been shown, using the same carbine, grenade launching cartridge, launcher, and grenade, and at the same elevation but with my auxiliary cartridge device included, as will be described. The invention is thus particularly important for use with the carbine, making this light weight weapon of service in a much wider scope, and particularly in grenade launching, where it has heretofore been of restricted value. Improvement in range with the rifles such as the Garand, Springfield and Enfield are also similarly manifest, and in the launching of rockets similar advantages are obtained. In the rifles, while the standard grenade launching cartridges for rifles produce higher velocities than the carbine ammunition, I am still able to use my auxiliary without change, using the same quantity of propellant component, with higher velocities and increased range, although not in the same relative proportion as with the carbine. The increased ranges with the rifle equal those with the carbines, however, and are all that are at present required for the improved utility of grenade firing. While a special rifle auxiliary cartridge with a larger charge similarly proportionate to the rifle grenade launching cartridge content may be made, it is not considered necessary or desirable in view of the ranges actually obtained with the single device, which simplifies manufacturing and supply procedure, and also avoids possibilities of mistake or confusion, such as might involve use of a heavy charge rifle auxiliary cartridge in the carbine launcher.

It is a specific aim of the invention to evolve a novel means for effecting ignition of an auxiliary propellant charge element, as well as to enable the ready incorporation thereof in a conventional grenade and grenade launcher in a simple way.

Additional objects, advantages, and features of invention reside in the construction, arrangement and combination of parts involved in the embodiment of the invention, and in the method of practice thereof, as will be more clearly apparent from the following description and accompanying drawings wherein:

Fig. 1 is a perspective view of the muzzle of a

rifle on which a conventional grenade launcher is shown, with my auxiliary cartridge and a grenade tail piece in position for loading.

Fig. 2 is a full size longitudinal section of the launcher with my auxiliary cartridge and grenade loaded.

Fig. 3 is a cross section on the line 3-3 of Fig. 2.

Fig. 4 is an enlarged longitudinal section of the auxiliary cartridge.

Fig. 5 is a similar view showing a preferred form of the auxiliary cartridge.

Fig. 6 is a representation of a fictitious set of curves representing at A, maximum strength of barrel; B, safety pressure allowance; C, conventional ball cartridge pressure curve; D, pressures produced by the small charge carbine size regular grenade launcher cartridge M6, and G, pressure increment of my auxiliary M7; as well as at H a general indication of the resultant of the two last named pressures during launching of a grenade.

Fig. 7 is a fictitious graph similar to Fig. 6 showing what is believed to be substantially the pressures in the grenade launcher tube during the firing operation.

Fig. 8 is a view of a primary propellant cartridge.

Reference is also made to the patents to W. T. Moore, No. 2,335,299, and J. C. Garand, No. 1,892,141, for details of the arm, attachment, and conventional practice with cartridges of propellant for use in launching grenades.

Referring more particularly to the drawings, there is illustrated one well known form of grenade launcher 10 attachable to and detachable from a rifle 11 or the like; the illustration showing only the muzzle end 12 of the rifle barrel, the forward extremity 13 of the stock, and part of the gas cylinder 14 of a well known automatic or semi-automatic rifle. The launcher 10 is of a well known construction with means to secure it detachably to the barrel with the tubular body or piston element 15 of the launcher alined and in gas receiving relation with the bore of the barrel. As is well known the launcher for the automatic rifle also includes means to cause venting of gases from the attached rifle otherwise than through the end of the barrel. None of these particular features of known structure other than the body of the piston are illustrated or described in detail herein, comprising no novel part of my invention. Construction of the grenade or other projectile to be launched also may remain unchanged as heretofore constructed, and details other than the tail-piece 16 and immediately connected part of a grenade body 17 are not illustrated. The tubular launcher piston 15 shown full size in Fig. 2, has the usual closely spaced narrow land rings 18 at the forward end, more widely spaced narrow intermediate land rings 19, and rearmost wide lands 20. The interior also is the usual smooth-bored cylindrical chamber 21 much larger in diameter than the bore of the rifle on which the launcher is applied, and opening flush through the forward end of the piston ordinarily but in this instance shown as flared or interiorly bevelled as at 22, at the mouth of the muzzle, affording a conical seat.

The grenade 17 may conform to approved practice for rifle grenades or may be varied to accord with improved practice, as may be found desirable. It has an interiorly threaded nipple 23 at its rear extremity coaxial with the center of gravity of the grenade, and into this there is screwed a corresponding tenon 24 of the head 25

of a tail piece tube 26, this tube being smoothly slidable upon the body or piston 15 of the launcher, and extending nearly to the rearmost wide land 20, the next forward wide land being within the tube and supporting the same in concentric relation to the launcher body. The tube has at its rear end the usual tail fins 27.

For use with the launcher and grenade with tail piece as above described, I have formed an auxiliary cartridge 28, somewhat resembling an ordinary shot gun shell, and loaded with an auxiliary charge of explosive. This cartridge in the present instance comprises a case 29 of cylindrical form, adapted to fit slidingly in the forward end 15 of the bore 21 of the launcher piston tube 15. It may fit loosely in the launcher so as to most certainly assure its free withdrawal with the grenade at the proper time. In the present instance the case 29 is formed with a head 30 having a peripheral flange 31 with a conical outer face arranged to fit the bevelled seat 22 or mouth of the tubular piston, and the head 25 is completely received in the bevelled seat clear from the extremity of the body 25. This auxiliary cartridge case may be formed of any low cost water proof expendable material, including paper, plastics, and metal; and in use, thus far, has been made of brass to expedite production. The case may be of such length as required to accommodate therewithin the auxiliary charge of explosive determined on. For rifles this may be varied in quantity between twenty to thirty grains or more of a powder produced by the E. I. du Pont de Nemours Company, of Wilmington, Delaware, and known as EX4809-6, of somewhat finer grain but of values similar to those of the standard powder used in the grenade firing cartridge, now standard for use in rifles. This latter standard cartridge ordinarily employs about forty grains of smokeless or "pro" powder, plus about five grains of FFFG black powder.

For the carbine this known grenade firing cartridge may be varied somewhat, but the charge in my auxiliary cartridge used in the U. S. carbine, caliber .30, M1, has consisted of from twenty to thirty grains of the powder EX4809-6 with satisfactory results, the larger amount giving a range of 390 yards with the carbine set with its butt against a stationary support and elevated to an angle of forty-five degrees, which is the standard angle for firing grenades from such weapons.

The charge is retained in the case 29 by means of a wad 33 which has heretofore been made of thin fast-burning cardboard, covered with a standard red lacquer 32. In one form the wad has been imperforate, as at 33 in Fig. 4, but preferably, for maximum range with a given charge, and to attain greater uniformity of performance, the wad is formed as at 34 in Fig. 5, with one or more relatively large perforations 35 covered with a filamentary sheet or septum 36 of waterproof quick-burning material. This has been made of tissue paper coated with shellac, and may also consist of such paper coated or saturated with a cellulose compound or an NH powder solution. The single hole 35 shown has been made approximately two fifths the diameter of the interior of the case. While I have heretofore used as the initial propellant a standard cartridge with a usual "pyro" powder, this may be modified if desired, by the use of a double base powder to attain a quicker peak pressure, and earlier action of the products of its combustion and to assure prompt ignition of the auxiliary charge. The burning and volumetric values and

characteristics of the auxiliary charge may also be modified with a view to obtaining pressure curve values and resultant composite curve corresponding to the effects represented as an objective of the invention in Fig. 7.

In the practice of my invention, manufacturing and shipping practices as heretofore followed are carried out, with those additional involved in producing the auxiliary cartridge. No special shipping cases, handling, or space will be required.

Thus, as is known, grenades are shipped in kits with a grenade-firing cartridge for a particular weapon packed in the tail tube of each grenade, and there is ample room for my auxiliary cartridge also in each tail tube. Other shipping practices are also possible.

In firing, usual practices may be followed as heretofore, in setting the gun and loading after applying the launcher, and the grenade may also be launched by firing the gun from the shoulder. The latter practice requires a knack of "leaning to the gun" for satisfactory results and may be carried out by men of moderate weight, as has been demonstrated. Owing to the coordinated timing of the explosion of my auxiliary charge, the force of the "kick" of the gun is not increased beyond that experienced when using the usual grenade-launching cartridge, but the recoil is longer sustained requiring the shoulder to be held firmly against the butt of the stock but yielding without the marksman becoming unbalanced rearward.

My auxiliary cartridge with a charge of twenty grains has been fired from the shoulder with good results.

The gun with launcher being ready, the auxiliary charge is set in place as shown and described, after which the tail tube of the grenade is slipped over the body of the launcher. A single grenade firing cartridge 38 is then introduced into the chamber of the gun accompanied by usual cocking of the weapon. The gun being properly emplaced or pointed, the trigger is operated to fire the first cartridge. The gases thus evolved move rapidly through the gun barrel and chamber of the piston with only moderate or relatively gradual rise of pressure, substantially as at D in Fig. 6, until opposed by the inertia of the grenade, when there will be a prompt rise to the peak of the pressure curve approximately as at E. Movement of the grenade and cooling will then quickly tend to cause a drop in the pressure curve. In the meantime, however, the covering of the auxiliary charge will have been burned, and the auxiliary charge ignited, producing an explosion acting in a direction counter to the preceding movement of the products of combustion of the first charge accompanied by high momentum in the newly evolved gases as well as added pressure, and, due to the relief of pressure which is then progressively occurring in the products of the first charge by cooling and expansive chamber action, the tendency of the second charge to build a maximum peak of its pressure while confined by the grenade on a curve such as at E, is first cushioned and somewhat relieved in the tube by a momentary further compression of the gases in the chamber 21 and gun barrel. It may be noted that the nature of the wad 33 is such that it

offers no material impedance to the discharge of gases from the shell 29 when fired and a high if not maximum expansion-pressure value is immediately derived from the second propellant charge 5 when fired, substantially as described above. With the foregoing and the accompaniment of the falling pressure curve of the first gases a more gradual rise of the pressure accretion is effected, approximately as at G, with a resultant aggregated effect approximated by the curve H. The fall of the latter curve will then parallel the curves of the first and second charges, maintaining a comparatively high pressure even in its descending part. This descending part of the curve 10 of aggregate pressures will coincide with the final movement of the tail sleeve from the piston or body of the launcher. In consequence of the effects noted, the pressure curves in the tube 26 will vary from those in the chamber of the fire-arm.

20 The case 29 is carried away with the grenade in the operation described although no material rocket effect is manifest in the performance of the grenade. The case falls near the gun.

25 The body of air in the rifle or carbine barrel and in the launcher chamber 21 is a material factor in delaying and determining the coordination of the explosion of the auxiliary cartridge, and the septum materials 33 and 36 serve as ignition propagating means as well as protective and slight delay means.

30 I claim:

1. In combination, a grenade-launching tube 35 constructed and arranged to be carried by its rear end, on the muzzle end of a firearm barrel, an auxiliary cartridge held in the forward end of said tube, the end of said cartridge facing the rear of the tube being adapted for ignition by propellant gases in the tube and the other end of 40 said cartridge being closed, and a grenade having a tube portion slidably fitted on the launching tube, said auxiliary cartridge being rearward of and a separate entity from the grenade whereby the said cartridge may be applied separately from 45 and prior to mounting of the grenade.

2. In the combination of claim 1, an annular shoulder on the forward end of said launching tube and a complementary annular portion on the cartridge whereby the motion of the cartridge 50 into the tube is limited.

CHARLES ROBERT OLSEN.
